UNITED STATES PATENT OFFICE.

GEORGE W. ERICSON, OF GALESBURG, ILLINOIS, ASSIGNOR TO WILLIAM E. HAMER-STROM, OF GALESBURG, ILLINOIS.

HOG-OILER.

1,238,900.

Specification of Letters Patent. Patented Sept. 4, 1917.

Application filed July 29, 1915. Serial No. 42,589.

To all whom it may concern:

Be it known that I, GEORGE W. ERICSON, a citizen of the United States, and a resident of Galesburg, in the county of Knox and 5 State of Illinois, have invented a new and useful Hog-Oiler, of which the following is a specification.

My invention relates to devices for supplying oil or other liquid to a plate adapted 10 for actuation by an animal rubbing thereagainst, whereby the liquid will be self-applied to his body, and it consists, substantially, in the improvements hereinafter described.

15 The principal end and object of the invention is to generally simplify and improve the construction, to increase the utility and efficiency of the device, and to decrease the expense attendant upon both its manufacture and use.

More specifically stated, it is an object to dispense with the usual centrally arranged leg and with several of the rubbing-plates ordinarily employed. In this connection it 25 is an object to so construct the device that it may be secured to a shed, barn, stable, fence, fence-post, tree, or any other suitable object.

To this general class or type of hog-oilers 30 the chief objection has been that when an animal leaned against the vertical rubbing-plate, whereby the oil-discharging means was operated, the oil would continue to flow as long as the pressure was maintained, the 35 major portion of the oil being wasted. To provide a device of this character which will permit the discharge of a measured quantity of oil at each reciprocation of the plunger or valve-stem, but in which provision is 40 made for cutting off the discharge of oil while the animal is merely leaning against the rubbing-plate, constitutes one of the most important objects of the invention.

It is an object to dispense with the usual 45 tank. In order to accomplish this object I provide a support for the can in which the oil is shipped to the user, and employ said can as the tank. It is not to be understood from the foregoing, however, that a tank 50 of the usual character can not be successfully embodied in my improvements.

A further object is to provide a suitable reservoir into which the can discharges oil and from which reservoir the oil passes to 55 the discharge means.

It is another object to provide a novel bearing for the rubbing-plate.

A special object is to provide a novel valve or cut-off.

An additional object is to provide a novelly arranged and novelly constructed belly-rubbing plate.

Other objects will presently appear. Some of these will be obvious and others particularly noted.

A preferred embodiment of the invention is illustrated in the accompanying drawings, wherein:

Figure 1 is a side elevation of a preferred embodiment of my invention;

Fig. 2, a front elevation, the belly-plate omitted;

Fig. 3, a vertical central fragmental section, its plane taken in the line 3—3 in Fig. 2;

Fig. 4, a transverse section of the reservoir; and

Fig. 5, a reduced top plan detail of the belly-plate.

2 designates a board or other support 80 which for the purposes of this specification may be termed a base. 3 indicates a reservoir secured thereto by screw-bolts 4, having a depression or cupped bottom 5 (Fig. 5) extending from front to back and provided by curved side walls 5^a, and having at each inner corner and slightly below its upper edge a supporting lug 6 on which an inverted oil-can 7 rests, the can thus becoming the tank usually made as a part of the 90 device. The can 7 shown is the ordinary one of commerce, having a handle 8 and spout 9, the latter extending to or slightly below the top of the walls 5^a. At the lower edge of the front wall of the reservoir is 95 an opening 10 for the passage of oil therefrom. A valve-casing 11 is cast integral with the reservoir, as is also a spout 12 which communicates with the bore of said valve-casing by means of an aperture 13 100 which lies in a higher horizontal plane than does the opening 10. 14, 14 designate forwardly projecting plate-guiding lugs also integral with the reservoir 3 and provided with registering apertures for the reception 105 of a plate-retaining bolt 15 which is engaged by a nut 16. 17 designates a valve-stem or plunger provided at its upper end with ears 18 arranged diametrically opposite each other and having registering eyes 19. The 110

stem 17 is provided with an axial recess 20 extending to near its lower end, where it communicates with smaller and larger transverse openings 21, 21' respectively, extending through the stem. The bore 20 of the stem is sufficiently deep to provide an oil-cup 20' which, together with the openings 21 and 21' receive a charge of oil at each downward movement (presently described) of said stem, the opening 21' being normally closed by the wall of the valve-casing.

22 indicates a dirt-excluding plug. 23 designates an apertured lug or bracket on the bottom of the reservoir 3.

15 Secured by bolts 24 and nuts 25 to the base 2 is a lower bracket 26 having oppositely arranged arms 27 provided with registering apertures which receive a bolt 28 engaged by a nut 29. 30 designates a lug projecting between the arms 27, and 31 indicates a web, both of which parts are integral with the casting 26. 32 indicates a plate connected by pins 32', 32'' with the lugs 28-30 respectively and serving not only to prevent animals becoming fast between the base 2 and the rubbing-plate 33 presently described, but also as a brace or support for the reservoir and parts integral therewith.

33 indicates a channeled rubbing-plate having at its upper end a rearward extension or gooseneck 34 provided with an aperture which receives a bolt 35 which passes also through the apertures 19 in the valve-stem ears. 36 indicates a nut on said bolt.

35 At its lower end the plate 33 has oppositely disposed rearwardly extending projections 37 provided with registering slots 38. 39 indicates a roller-bearing mounted on the bolt 28 and in the slots 38. Near its upper

40 end said plate is provided with an opening 55 toward which the spout 12 is directed, the lower wall of said opening being provided by a shelf or ledge 40 onto which the oil drops from said spout. On its face said plate is provided with oppositely arranged obtuse angled embossments or spreaders 41 comprising each a vertically and a downwardly inclined branch, the inclination of the latter being in an alternate series, or 45 each one inclined in a direction opposite to that of the adjacent one.

42 indicates a belly-rubbing plate secured by a pin 43 to the lug 31. The upper face of its outer portion is channeled to receive and retain any oil which may drip from the plate 33—see Figs. 1 and 5. 44 designates one of a pair of braces (the other not shown) arranged on opposite sides of the plate 42 and connected thereto and to the base 3 by bolts 45-46 respectively.

In order to hold the can securely but removably on the lugs 6 I provide an L-shaped bracket 47 having a locking projection 48. The bracket 47 is pivotally secured to the base, as by a bolt 49 and wing-nut 50, where-

by when it is desired to remove the can from the position shown it may be done by slightly loosening said nut and swinging the bracket to one side. To lock the can in place a reverse operation is performed.

In operation, the animal will rub against the plate 33 which will move freely on its roller-bearing 39, and the walls of the inclined slots 38 will carry said plate and thereby the valve-stem upward. As hereinabove stated, the openings 21, 21' are filled with oil at each downward movement of said stem. This small, measured and inexpensive quantity of oil will, when the stem is raised as just described—whereby the opening 21' comes on a level with the opening 13—flow from the former into the latter and thence down the spout 12, from which it will drop onto the shelf 40 and thence flow down upon the plate. Inspection of Fig. 3 will show that when the openings 13 and 21' register, as just described, the lower end of the plunger 17 has risen to a horizontal plane above the lower edge of the outlet 10 of the reservoir, thereby permitting the oil to flow into the bottom of the valve-casing. Then, upon the return or down stroke of the plunger it will completely fill the casing, thereby forcing back into the reservoir that oil which had occupied the lower portion of the casing. When medicated or mixed oils the constituents of which are of different specific gravities are used, the force of the backward-rushing oil will stir up and thoroughly commingle said constituents and the supply will not be drawn from the heaviest alone thereof, as in the case of preceding devices of similar nature. Moreover, should the solid ingredients of the oil collect in the passage between the reservoir and valve-casing, the forcibly driven, backward moving oil will wash out and cleanse said passage. Inasmuch as the plate 41 is necessarily heavy, in order to withstand rough contacts by the animals, its gravity will tend to jerk the plunger rapidly down, whereby to drive the oil back with like rapidity. Should the oil flow very freely (because of the rapid and continued movements of the animal against the plate, and consequent rapid reciprocations of the valve-stem) it will flow from the terminal of each of the inclined branches of the embossments 41 and strike the vertical branch of the one below, and so on in an evident manner; but if it comes slowly it will merely drip from one inclined branch onto the one below. Should the animal bear against the vertically arranged plate in such manner as to cause the valve-stem to be held for a period of time in open or oil-discharging position, no oil other than that carried in the valve-stem will be discharged, for none can flow from the reservoir thereinto until the valve-stem has dropped to its normal position. Any excess

oil will drip from the plate 33 into the cup 51 in the plate 42 and will be distributed over the bellies of the animals rubbing thereagainst.

5 It has been thought neither necessary nor best to encumber this specification and the accompanying drawings with descriptions and illustrations of modifications which are not essential to the invention, viewed in its 10 broadest aspect. In fact, it will be apparent without such that some of the features herein disclosed may be used without the others; that some may be embodied in devices similar in nature but vastly different in 15 structural characteristics; that some may be dispensed with; that the arrangement and disposition of some of the elements may be changed; and that many changes may be made in the details of construction. All of 20 these changes I comprehend as residing within the scope of the invention. Therefore, without limiting myself to particularities, except where such are specifically pointed out, I claim as new the following, 25 namely:

1. Combined in an animal oiler, a source 30 of liquid-supply having an outlet immediately above its bottom, a valve-casing communicating therewith and having an outlet, the latter arranged in a higher horizontal plane than the former, a valve fitting snugly 35 in the casing and having an axial opening extending from its top almost to its bottom and adapted to contain a charge of liquid, and having also a transverse inlet and a 40 transverse outlet, the former normally communicating with the source of liquid supply, the bottom of the valve adapted to rise above the first recited outlet, and means actuatable by an animal whereby to cause said valve 45 to rise and to discharge the liquid contained in its axial opening into the outlet in the valve casing.

2. In combination, a valve casing having 50 an inlet immediately above its bottom and having an outlet in a higher horizontal plane than the inlet, a supply-vessel communicating with said inlet, a valve having an axial opening extending from its top nearly to its bottom, having an inlet communicating with the inlet in the valve casing, and having an 55 outlet, the liquid from the supply vessel adapted to pass into and fill the axial opening in the valve, and means for raising the valve to such position that its outlet will register with the outlet in the valve-casing and the liquid will flow from the axial opening in the valve out through the outlet in the casing.

60 3. In combination, a valve casing having an inlet immediately above its bottom and having an outlet in a higher horizontal plane than the inlet, a supply-vessel communicating with said inlet, a valve having an axial 65 opening extending from its top nearly to

its bottom, having an inlet communicating with the inlet in the valve casing, and having an outlet, the liquid from the supply-vessel adapted to pass into and fill the axial opening in the valve, a rubbing-plate for 70 raising the valve to such position that its outlet will register with the outlet in the valve-casing and the liquid will flow from the axial opening in the valve out through the outlet in the casing and onto said plate, 75 and a horizontally arranged rubbing-plate adapted to catch the drip from the first recited rubbing-plate.

4. In a device of the character described, a reservoir having an outlet, a valve casing 80 communicating with said outlet, a hollow valve adapted to receive liquid from the first recited outlet and its lower end adapted to rise to a horizontal plane above the lower edge thereof, whereby to permit liquid to 85 flow from the reservoir into the casing, and a movable element adapted in one of its movements to so move the valve that it will discharge the liquid from its hollow portion and in another of its movements drive back 90 into the reservoir the liquid which entered the casing when the lower end of the valve rose above the lower edge of the reservoir outlet.

5. In a device of the nature described, a 95 source of oil-supply, a valve communicating therewith, a rubbing-plate connected with and adapted to operate said valve, said plate provided near its lower end with an inclined slot, a roller arranged in said slot, and means 100 for supporting the roller.

6. In a device of the nature described, a source of oil-supply, a valve communicating therewith, a rubbing-plate connected with and adapted to operate said valve whereby 105 to discharge oil onto said plate, said plate provided near its lower end with an inclined slot, a roller arranged in the slot, means for supporting the roller, and a horizontally arranged rubbing plate adapted to catch the 110 drip from the first recited rubbing-plate.

7. A device of the character described including in combination, a support having a receptacle for holding liquid, a rubbing member having an inclined slot at its lower 115 end, a pin connected to said support and passing through said slot whereby the rubbing member has a slidably and pivotal connection with said support whereby it may be raised and swung relative thereto, a vertically movable transfer member for receiving liquid from said receptacle and transferring same to said rubbing member, and connections between said rubbing member and said transfer member for moving the transfer member to liquid-receiving position when the rubbing member is lowered, and for moving the transferring member to discharging position when the rubbing member is raised.

8. A device of the character described including in combination, a supporting member having a source of oil supply thereon, a valve member controlling the discharge of oil from said source of supply, a rubbing member adapted to operate said valve member and having an inclined slot near its lower end, and a pin connected to said sup-

porting member and passing through said slot whereby the rubbing member is slidably 10 and pivotally secured to said supporting member.

In testimony whereof I hereto affix my signature, this 24th day of July, 1915, at Galesburg, Knox county, Illinois.

GEORGE W. ERICSON.
